HEEL

Eugene J. Korda, New York, N. Y.

Application December 28, 1939, Serial No. 311,423

8 Claims. (Cl. 36—34)

This invention relates to heels for women's shoes and more particularly relates to fabricated metal heel arrangements of simplified self-reinforcing construction which are light in weight.

Among the objects of the present invention is to provide metallic heels for ladies' shoes, suitable for economic mass production; formed of flat metallic sheets, using ordinary sheet metal fabricating or extrusion operations; self-reinforced when assembled for strength and lightness in weight; and well appearing and attractive for ornamental effects.

These and other objects and features of the invention will appear from the subjoined detailed description of specific embodiments thereof illustrated in the accompanying drawings, in which:

Figure 1 illustrates one form which the unitary heel construction of the invention may assume in practice, assembled on a shoe.

Figure 2 is a perspective illustration of the unitary heel assembly of Figure 1.

Figure 3 is a disassembled view of the heel of Figures 1 and 2.

Figure 4 is a development of a metallic sheet comprising the bent-up portion of the heel of Figures 1 to 3.

Figure 5 is a modified plan view of the heel portion corresponding to Figure 4.

Figure 6 is a perspective view of a modified heel, assembled on a shoe.

Figure 7 is a disassembled view of the heel of Figure 6.

Figure 8 is a plan view of a fabricated central portion of the heel of Figures 6 and 7.

Figure 9 is a perspective view of still a further form of the metallic heel of the invention.

Figure 10 is a plan view in section along lines 10—10 of Figure 9.

Figure 11 is disassembled view of the heel of Figure 9.

Figure 12 is a vertical cross-sectional view through the heel construction of Figure 9, illustrating a preferred way of attaching the heel to the body of the shoe.

Figure 13 is an enlarged detailed sectional view through the preferred heel attaching means of Figure 11.

Referring to Figure 1, I illustrate a simple rigid heel construction comprising two vertical portions 20, 21 joined by an intermediate integral section 22 and an upper plate 23, to which flanges 24 and 25 at the top of members 20 and 21 respectively are secured. A leather or rubber lift

or heel portion 26 is secured to the bottom of the heel body.

A perspective view of the unitary heel construction in Figure 1 is shown in Figure 2. Plate 23 is attached to the bottom 27 of the shoe and is either flat or has a curvature corresponding to the shape of coacting sole 27. The upright supporting members 20, 21 taper outwardly longitudinally and are bowed transversely from the relatively narrow bottom portion 22 to the larger upper plate 23.

A disassembled view of the heel of Figures 1 and 2 is shown in Figure 3, wherein top plate 23 is separated from the fabricated portion 20, 21, 22. Flanges 24, 25 are contiguous with the upright sections 20, 21 respectively, and are welded, brazed, riveted or otherwise secured with the metallic plate 23 to form a rigid-self-supporting heel assembly.

The central body of the heel of Figures 1 to 3 is formed of a flat metallic sheet, as illustrated in Figure 4. The corresponding sections of the heel body are represented by the corresponding numerals, and are separated by dotted lines, which represent bending regions for fabrications. The shape of the metallic sheet is such that when bent on the dotted lines defining the bending zones, the heel body illustrated in Figure 3 is formed.

Figure 5 shows an alternate arrangement for constructing the heel of Figures 1 to 3. In this case, flange 25 is omitted, and the upper plate 23 is integral with the unitary central sheet, as shown at 23'. In this case, by bending along the dotted lines of Figure 5 and joining flange 24 with the corresponding edge of member 23', a unitary heel construction corresponding to Figure 2 results. The lift 26 shown in Figures 1 and 2 is suitably secured to the bottom of central portion 22 to complete the heel assembly.

The heel construction described in connection with Figs. 1 to 5, as well as those to be described hereinafter, have a common factor in being unitary with respect to the remaining shoe; being formed of flat metallic sheets cut, bent, and otherwise fabricated by simple standard mass production methods; and assembled in a hollow or open construction which is self-strengthening and has a pleasing and ornamental appearance.

Figures 6, 7 and 8 show another form which my invention may assume in practice. Figure 6 is a perspective view of heel 30 secured to the rear portion of sole 31 of the body of a shoe. Heel 30 comprises a central member 32 of criss-cross form giving a definite ornamental effect,

and which is secured at the top to a metallic coupling plate 33. A leather or rubber heel 34 is suitably secured directly to the bottom of central portion 32, or may be joined to an intermediate metallic plate secured to portion 32.

Figure 7 is a disassembled view of heel 30 showing coupling plate 33 and heel section 34 separated from the fabricated body portion 32. Flanges 35 extending from the bottom sections of portions 32 are used to join central body 32 with heel 34. Corresponding flanges 36 at the top portion of member 32 are bent over at substantially 90° and joined with metallic coupling plate 33 by riveting, welding, or equivalent manner.

Figure 8 shows a development of a metal sheet used in fabricating body portion 32. Cut-out portions of body 32 are such as to result in the heel illustrated in Figures 6 and 7, when bent up to that form. Openings 37 and 38 therein form the central openings of the heel, enhancing the design and ornamental appearance of the heel. Portions 39 are bent over in a flange form to serve as a reenforcing means for the heel when assembled, as shown in Figures 6 and 7. The assembled heel is a unitary construction, light in weight and having ample strength in service.

Figures 4 to 12 illustrate still a further form which my invention may assume in practice. In this example, heel 50 is formed of two interlocked vertical members 51 and 52 joined to a coupling piece 53 and a heel section 54 at the bottom of which lift 55 is secured. The disassembled view, Figure 10, of heel 50 clearly illustrates the interlocked assembly thereof. Uprights 51 and 52 have coacting slotted sections 56 and 57 which are slid together for the interlocking.

Upper flanges 58, 59, 60 and 61 form a common plane when upright members 51 and 52 are interlocked in the assembled form shown in Figure 9. Flange sections 58 to 61 are accordingly readily riveted, welded or otherwise joined to heel coupling piece 53 due to their common plane. Similarly, bottom flanges 62, 63, 64, 65 form a common plane for securing to metallic heel piece 64. The assembled metallic heel forms a unitary construction of pleasant appearance of rigid self-supporting, self-strengthening design.

A preferred method of assembling the metallic heels of the invention to the body of the shoe is illustrated in Figures 11 and 12, specifically in connection with heel 50 of Figures 9 and 10. Heel plate 53 is secured to shoe 70 by rivets 71. Four rivets, such as 71, passing through openings 72 shown in plate 53 of Figure 11, are generally sufficient. Figure 12 is an enlarged sectional view through a portion of the rivet section showing rivet 71 holding heel plate 53 together with shoe section 70 comprising a plurality of layers including an inner sole, fiber or leather counterlining, and other usual shoe layers.

The outer edge 73 of heel plate 53 is curved over, resulting in its edge digging into the body of the shoe 70 to obtain a firm grip. A suitable padding or lining 74 is placed inside the heel section of the shoe, as shown in Figure 12, to cover up the inner heads of rivets 71.

The heel plate of the unitary shoe of the invention need only be made in small, medium and large sizes and with a minimum degree of curvature. Its edge, corresponding to edge 53, is forced upward by a U-anvil to fit close to the shoe and firmly grip it. Another method is to employ heel plates of different sizes, leaving the heel of the shoe the same size. In this manner, heels for different sizes of shoes can be provided

in an economical manner in commercial production.

Although I have referred to spot welding or brazing with respect to the flanges, such as 24-25 and 35-36 and the like, it is within the province of this invention to eliminate the flanges and to braze or weld the edges of the intermediate sections directly to the upper or lower heel plates, as the case may be.

Although I have described the formation of the heel of sheet metal or the like, it is within the province of this invention to form the heel of plastic or like non-metallic materials.

Although I have described preferred arrangements for carrying out my present invention, it is obvious that various changes and modifications may be made to the details of construction without departing from the general spirit of the invention as set forth in the appended claims.

I claim:

1. A shoe heel comprising a plate shaped for coupling an upper heel region with the body of a shoe, an open upstanding heel section incorporating spaced supports mechanically secured with said plate, and a formation extending at least partially across and secured with the bottom region of said upstanding heel section to form a rigid unitary heel assembly.

2. A shoe heel comprising a metallic plate shaped for coupling an upper heel region with the body of a shoe, an open upstanding metallic heel section incorporating spaced supports mechanically secured with said plate, and a formation extending at least partially across and secured with the bottom region of said upstanding heel section to form a rigid unitary metallic heel assembly.

3. A unitary shoe heel comprising a metallic plate shaped for coupling an upper heel region with the body of a shoe, an open upstanding metallic heel section formed of a unitary metallic plate incorporating spaced supports tapering outwardly from the bottom region to the upper plate and being secured with said plate along the upper region thereof, and a formation extending at least partially across and secured with the bottom region of said upstanding heel section.

4. A unitary metallic shoe heel comprising a metallic plate, an open intermediate metallic section containing flanged edges mechanically secured with said plate, said section being formed of a unitary metallic plate containing a central portion arranged substantially flat for holding a lift.

5. A unitary metallic shoe heel comprising a metallic plate, an open intermediate metallic section containing flanged edges mechanically secured with said plate, said section being formed of a unitary metallic plate containing a central portion arranged substantially flat for holding a lift, said intermediate section having upright members tapering outwardly from the bottom region to the upper plate.

6. A unitary metallic shoe heel comprising a metallic plate shape for coupling the upper heel region with the body of a shoe, an open upstanding metallic section incorporating spaced supports mechanically secured with said plate, said section being formed of a unitary metallic plate for holding a lift.

7. In combination with a shoe structure, a unitary heel comprising a metallic section having outwardly tapering upright members, and

inwardly extending sets of flanges at the extremities of the upright members, said section being attachable to the shoe structure at one of the sets of flanges.

8. In combination with a shoe structure, a unitary heel comprising a metallic section having outwardly tapering upright members, and in-

wardly extending sets of flanges at the extremities of the upright members, said section being attachable to the shoe structure at one of the sets of flanges, and a heel lift being attachable to the section at the other of said set of flanges.

EUGENE J. KORDA.
